UNITED STATES PATENT OFFICE.

SAHATIEL G. MANDALIAN, OF NORTH ATTLEBORO, MASSACHUSETTS.

ORNAMENTAL ROPE.

Application filed January 27, 1922. Serial No. 532,224.

To all whom it may concern:

Be it known that I, SAHATIEL G. MANDALIAN, a citizen of the United States, residing at North Attleboro, in the county of 5 Bristol and State of Massachusetts, have invented certain new and useful Improvements in Ornamental Rope, of which the following is a specification.

My invention relates to a rope adapted for 10 use in bracelets, necklaces, handles for bags, and other useful structures wherein a rope forms a constituent part or is employed as a binding agent, or otherwise.

The essential objects of my invention are 15 to insure a maximum of strength and durability combined with flexibility, pliability, lightness, and softness; imperviousness to wear or injury; and capacity for ornamental effects. Other objects and advantages will 20 be disclosed by an inspection of the following specification.

To the above ends essentially my invention consists in such parts and in such combinations of parts as fall within the scope of 25 the appended claims.

In the accompanying drawings which form a part of this specification,

Figure 1 is a side elevation of a length of rope embodying my invention,

30 Figure 2, a central longitudinal section of the same showing the interior in side elevation,

Figure 3, an end elevation of the same,

35 Figures 4 and 5, an enlarged fragmentary side elevation and vertical section respectively of one form of mesh sheath construction,

Figures 6 and 7, side elevations of other forms of mesh sheath construction, and

40 Figure 8, an end elevation of a modified form of my novel rope.

Like reference characters indicate like parts throughout the views.

My rope comprises a flexible metallic 45 sheath or armor 10 capable of resisting external blows, and of imparting great resistance to longitudinal or other tensile strain. The sheath consists of a flexible metal fabric having interstices 11 which permit visibility, to a limited extent, of the color or the material enclosed by the sheath.

The preferred form of mesh fabric, which is shown in Figures 4 and 5, is a scale mesh, formed by parallel rows of rings 13, each 55 four adjacent rings being interlocked with a flat link or plate 14 of cruciform shape

by four corner prongs 15 converging in the rear of the plate.

A metallic fabric of ring mesh which may constitute the sheath comprises parallel 60 rows of ring links 17, each group of four rings being engaged by a ring 18, as shown in Figure 6.

In Figure 7 is shown another alternative sheath structure consisting of a lock link 65 mesh fabric. Herein the links are arranged in rows, and each U shaped folded link 19 has terminal loops 20 through which pass the links of an adjacent row.

In all three forms of link mesh it will be 70 observed that the links are loosely interengaged.

Within the sheath 10 is a core 22 or body of relatively soft pliable material such as 75 thread or yarn united in strands and longitudinally twisted or braided. The form of core herein shown consists of soft threads 23 loosely twisted to form strands 24 which in turn are loosely twisted to form the core. The core thoroughly fills the sheath and 80 frictionally engages the same and the core combined with the sheath constitutes the rope.

In Figure 8 is shown a modification of 85 my invention wherein the mesh sheath 10 is elliptical in cross section, and the core consists of a length of tubular woven fabric or webbing 26. As described the mesh sheath of thin metal parts affords, because 90 of its interstices a visibility of the color of the core which may be any shade desired.

The flexible character of the mesh admits 95 bending and twisting of the rope. Its metallic character insures not only strength and durability but also enables the rope to sustain great strain. The soft core contributes to the flexibility of the chain as well as the pliability thereof. The rope because of its structure is exceedingly light as well as strong, and combines increased utility with 100 beauty of appearance.

I claim:

1. An ornamental rope comprising a pliable core, and a metallic link mesh sheath surrounding and engaging the core.

105

2. An ornamental rope comprising a soft pliable core and loosely interlocking links embracing and surrounding the core.

In testimony whereof I have affixed my signature.

SAHATIEL G. MANDALIAN.
